INDUCTION HEATER

Edgar F. Caswell, Detroit, Mich., assignor to
 Kelsey-Hayes Wheel Company, Detroit, Mich.,
 a corporation of Delaware

Application August 30, 1948, Serial No. 46,892

5 Claims. (Cl. 219—47)

1

The invention relates to induction heaters and refers more particularly to induction heaters for articles having annular flanges and backs with the latter provided with openings.

The invention has for one of its objects to provide an improved induction heater employing means for centering and moving the article to operative position with its annular flange extending within an annular electrical conducting element and separate means for moving a magnetic flux conducting field element to operative position within the annular flange, the two means being subject to fluid under the same pressure and the construction being such that the article is moved prior to the field element.

The invention has for another object to so construct the induction heater that the ratio of the resistance to movement of the article moving means to the resistance to movement of the field element moving means is less than the fluid pressure area of the article moving means to the fluid pressure area of the field moving means to secure the desired sequence of movement of the article and the field element.

With these and other objects in view, the invention resides in the novel features of construction and combinations and arrangements of parts as more fully hereinafter set forth.

In the drawings:

Figure 1 is a vertical section through an induction heater embodying the invention;

Figure 2 is a top plan view thereof partly broken away.

As illustrated in the present instance, the induction heater is designed for use with a brake drum shell having the annular flange 1 and the back 2 provided with the central hub receiving opening 3. The heater has the base 4 and the head 5 above and supported on the base by the rods 6. The head carries the annular upper magnetic flux conducting field element 7 and the annular low frequency electrical conducting element or winding 8. The field element is formed of the radially extending sections 9 below and secured to the head by suitable means such as the angle irons 10 and 11 welded to both the head and sections. Each section has the vertical portion 12 and the horizontal radially inwardly extending portion 13. The winding 8 is located within the vertical portions 12 and below the horizontal portions 13 and is of a size to encircle the annular flange 1 when the shell is raised to operative position. The winding is held in place by suitable means such as the plates 14 engaged by the nuts 15 threaded on the rods 16. The

2

plates are sleeved on the rods and the rods are located between the sections 9 and threaded in the head 5. The parts of the lower surfaces of the horizontal portions 13 radially inwardly of the winding are preferably shaped to substantially fit the upper or outer side of the back 2 of the shell when the latter is in its operative position.

The induction heater also has the annular lower magnetic flux conducting field element 17 adapted to be raised to operative position to cooperate with the field element 7 and the back 2 of the shell to conduct the lines of flux induced by electric current flowing through the winding around the annular flange 1 of the shell to there-by heat the latter. The field element 17 is formed of the radially extending sections 18, each of which is in vertical alignment with a section 9 of the upper field element and has the vertical portion 19 of a size to extend within the annular flange 1 of the shell and the horizontal radially outwardly extending portion 20 which in the operative position of the field element 17 extends closely adjacent to the lower end of the vertical portion 12 of the section 9 above the section 18. The vertical portion 19 preferably has its upper face shaped to substantially fit the lower or inner face of the back 2 of the shell and this upper face is preferably engageable with the back to clamp the same against the portion 13 of the upper section above the lower section. The sections 18 are mounted on the table 21 and secured to the table by angle irons in the same manner as the sections 9 are secured to the head 5. The table is supported upon the combined piston and cylinder 22 which is vertically reciprocable within the vertical cylinder 23 mounted on the bottom plate 24 fixedly secured upon the base 4.

The brake drum shell is supported when in in-operative position upon the rods 25 which extend upwardly between adjacent sections 18 of the field element 17. The upper end of each of these rods is preferably cut away to form the supporting face 26 for the annular flange of the shell and the guide 27 engageable with the radially outer face of the annular flange. The rods are mounted on the plate 28 which is secured to the upper end of the cylinder 23 by means of the rods 29 which at their lower ends threadedly engage the bottom plate 24.

For centering the brake drum shell relative to the winding 8 and also raising the brake drum shell to operative position, there is the pilot 30 having the frusto-conical portion 31 engageable with the edge of the opening 3 in the back of the shell and also having the support portion 32

engageable with the under or inner side of the back 2 of the shell. This pilot is carried by the piston 33 which is vertically reciprocable within the combined piston and cylinder 22 and is adapted to first center the shell and then raise the same with its back against the radial portions of the sections of the upper field element and with its annular flange within the winding.

The combined piston and cylinder 22 is slidably guided at the upper end of the cylinder 23 and is provided at its lower end with suitable sealing means 34 slidably engageable with the cylinder. The piston 33 is slidably guided at the upper end of the combined piston and cylinder 22 and is provided at its lower end with suitable sealing means 35 slidably engaging the combined piston and cylinder.

The bottom plate 24 forming the lower end of the cylinder 23 is provided with the port 35 for the passage of fluid under pressure such as compressed air into and from the lower end of the cylinder 23 both radially inside and radially outside the combined piston and cylinder 22. The lower faces of the combined piston and cylinder 22 and the piston 33 are simultaneously subject to this fluid under pressure.

For the purpose of centering the brake drum shell and raising it to operative position prior to raising the lower field element to operative position, the ratio of the resistance to movement of the piston 33 to the resistance to movement of the combined piston and cylinder 22 is less than the ratio of the area of the piston to the area of the combined piston and cylinder, so that when fluid under pressure is admitted to the lower end of the cylinder 23 the piston is raised to its full extent before the combined piston and cylinder is raised. The resistance to movement of the piston 33 is the result of the combined weights of the brake drum shell, the pilot 30 and the piston 33 plus the friction between the piston 33 and the combined piston and cylinder 22. The resistance to movement of the combined piston and cylinder is the result of the combined weights of the lower field element 17, the combined piston and cylinder 22 and the intermediate parts including the table 21 plus the friction between the combined piston and cylinder 22, the piston 33 and the cylinder 23. Another manner of stating the ratio between the parts to secure the desired operation is that the pressure of the fluid entering the cylinder 23 on the area of the piston 33 minus the resistance to movement of the piston 33 is greater than the pressure of the fluid entering the cylinder 23 on the area of the combined piston and cylinder 22 minus the resistance to movement of the combined piston and cylinder 22.

From the above description, it will be seen that I have provided a construction of low frequency induction heater in which the article having the annular flange to be heated is first raised to operative position after which the lower field element of the heater is raised to operative position and in which the means for effecting the raising of the article and the lower field element are separate but subject to fluid under the same pressure and the resistances to movement of these means and their fluid pressure areas are such that the desired sequence is secured.

What I claim as my invention is:

1. An induction heater for an article having an annular flange and a back provided with an opening, comprising an annular electrical

conducting element of a size to encircle the annular flange, an annular magnetic flux conducting field element adjacent said electrical conducting element, a piston having a pilot engageable with the edge of the opening in the back, said piston being movable to operative position for positioning the article with reference to said electrical conducting element and for also positioning the article with its annular flange extending within said electrical conducting element, a second annular magnetic flux conducting field element of a size to extend within the annular flange and shaped to cooperate in operative position with said first mentioned field element to conduct lines of magnetic flux induced by said electrical conducting element around the annular flange, and a combined piston and cylinder for moving said second mentioned field element to operative position, said piston and said combined piston and cylinder having areas subject to fluid under the same pressure and the ratio of the resistance to movement of said piston and the article to the resistance to movement of said second field element and said combined piston and cylinder being less than the ratio of the fluid pressure area of said piston to the fluid pressure area of said combined piston and cylinder whereby said piston is moved prior to movement of said combined piston and cylinder.

2. In an induction heater for an article having an annular flange and a back provided with an opening, an annular electrical conducting element of a size to encircle the annular flange, a pilot engageable with the edge of the opening in the back to center the article and also engageable with the back to carry the article, said pilot being movable to operative position to locate the article with its annular flange extending within the electrical conducting element, a magnetic flux conducting field element of a size to extend within the annular flange, a member carrying said pilot and a member carrying said field element, said members having areas subject to fluid under the same pressure and the resistances to movement of said members and their areas being such that the area of said first mentioned member multiplied by the pressure of the fluid minus the resistance to movement of said first mentioned member is greater than the area of said second mentioned member multiplied by the pressure of the fluid minus the resistance to movement of said second mentioned member whereby said first mentioned member is movable prior to movement of said second mentioned member.

3. An induction heater for an article having an annular flange and a back provided with an opening, comprising an annular electrical conducting element of a size to encircle the annular flange, an annular magnetic flux conducting field element adjacent said electrical conducting element, a pilot engageable with the edge of the opening in the back, a second annular magnetic flux conducting field element, means for moving said pilot towards said first mentioned field element to position the article with its annular flange extending within the electrical conducting element, and other means for moving said second mentioned field element to extend within the annular flange and to cooperate with said first mentioned field element to conduct lines of flux around the annular flange, both of said means being operable by fluid under the same pressure and the ratio of the resistance to movement of said first mentioned means to the re-

sistance to movement of said second means being less than the ratio of the fluid pressure area of said first mentioned means to the fluid pressure area of said second mentioned means whereby said first mentioned means is moved prior to said second mentioned means.

4. An induction heater for a brake drum shell having an annular flange and a back provided with a central opening, comprising an annular electrical conducting element of a size to encircle the annular flange, an annular magnetic flux conducting field element adjacent said electrical conducting element, a pilot engageable with the edge of the central opening in the shell back, an annular magnetic flux conducting field element, means for moving said pilot toward said first mentioned field element to position the shell with its annular flange extending within said electrical conducting element and other means for moving said second mentioned field element to operative position cooperable with said first mentioned field element to conduct lines of flux around the annular flange of the shell, said pilot moving means and said second mentioned field element moving means comprising concentric members operable by fluid under the same pressure.

5. An induction heater for an article having an annular flange and a back provided with a central opening, comprising a horizontal electrical conducting winding of a size to encircle the annular flange, an annular magnetic flux conducting field element having a portion encircling said winding and a generally radially inwardly extending portion for engagement with the back, a vertical cylinder below said winding having a port at its lower end for the passage of fluid under pressure, a second annular magnetic flux conducting field element having a portion of a size to extend within the annular flange

and a second generally radially outwardly extending portion, said portions of said second field element in its operative position being cooperable with said portions of said first mentioned field element to conduct lines of magnetic flux around the annular flange, a combined piston and cylinder vertically reciprocable within said cylinder and carrying said second field element, a pilot engageable with the edge of the opening in the back to center the article and also engageable with the back to carry the article and a piston vertically reciprocable within said combined piston and cylinder and carrying said pilot, said combined piston and cylinder and said piston having areas subject to the fluid under pressure entering through the port of said cylinder, and the ratio of the resistance to movement of the article, said pilot and said piston to the relative resistance to movement of said second field element and said combined piston and cylinder being less than the ratio of the area of said piston to the area of said combined piston and cylinder whereby the article is centered and raised against said first mentioned field element prior to raising of said second field element to operative position.
